TRACK AND VEHICLE THEREFOR, PARTICULARLY FOR USE AS TOYS

Hugo Victor Flinn, Cooleen, Rushbrooke, Cobh, Eire

Application July 30, 1938, Serial No. 222,129
In Great Britain June 8, 1937

16 Claims. (Cl. 104—164)

This invention relates to rail tracks and vehicles therefor and refers more particularly but not exclusively to such tracks and vehicles which are intended for use as toys.

The object of the invention is the provision of an improved apparatus of this character, and, in accordance with the invention, the track is essentially a monorail track mainly constituted by wire in a state of tension and the vehicle comprises one or more pulley wheels which run on said track and from which the main body of the vehicle is preferably suspended.

In order that the invention may be the more clearly understood a toy railway system in accordance therewith will now be described, reference being made to the accompanying drawings, wherein:

Figure 1 is a perspective view of a closed loop toy railway in accordance with the invention.

Figure 2 is a side elevation of a point switch employed in the loop railway of Figure 1, said point switch being in its normal or straight through position.

Figure 3 is a sectional plan of the same on the line 3—3 of Figure 2.

Figure 4 is a similar view to Figure 3 showing the switch in its other position.

Figure 5 is a cross section on line 5—5 of Figure 3.

Figure 6 is a cross section on line 6—6 of Figure 3.

Figure 7 is a side elevation of an alternative point switch in its normal or straight through position.

Figure 8 is a plan of the same.

Figure 9 is a similar view to Figure 8 showing the switch in the other position.

Figure 10 is a plan of a cross-over employed in the railway of Figure 1.

Figure 11 is a side elevation of the same.

Figure 12 is a diagrammatic plan of a so-called lay-by illustrating the way in which the latter can serve in the capacity of a turntable.

Figure 13 is a plan of an adjustable corner piece which may be employed in the system.

Figure 14 is a cross-section on line 14—14 of Figure 13.

Figure 15 is a side elevation of the portion shown in cross-section in Figure 14.

Figure 16 is a cross-section of a dual conductor which may be employed in the system.

Figure 17 is a similar view of a slight modification of Figure 16.

Figure 18 is a cross-section of an end structure

or corner piece which may be employed in the system.

Referring first to Figure 1, this shows a closed loop monorail and a vehicle 1 provided with overhead pulley wheels 2 and 3 which are adapted to run on said monorail and from which the vehicle is suspended.

The closed loop monorail may be of oblong form as shown having straight sides and curved ends, the two ends being comprised in respective rigid structures 4 and 5 and the sides being constituted by wires 6 and 7 in a state of tension between said two structures.

Each of the two end structures 4 and 5 may consist of a rigid horizontal plate structure having a curved edge at which is an upwardly projecting flange 8 constituting the curved end of the track. These upwardly projecting flanges may be bent over and thus made hollow and the wire lengths 6 and 7 forming the sides of the track may extend through them so that the wire itself forms a continuous loop. Or two separate lengths of wire 6 and 7 may be connected between opposite ends of the flanges by soldering, grub screws or the like. It is preferable that even where the wire passes through the flange 8 it should be fastened at the entrance and exit by soldering, grub screws or the like to reduce the collapsing strain on the curve. In either case the flanges will be preferably extended as shown a short distance beyond the main portion of the plate in a direction tangential to the curve, these extensions having lateral resistance but being bendable. Thus the stress on the plate comes as a straight pull and the angle of any wire not tangential to the curve is made smooth.

The end structures, including the flanges, must be strongly and rigidly made as they must serve to hold the wire in considerable tension so as to prevent it from sagging when it is supporting the weight of the vehicle.

Within the confines of the closed loop monorail and supported thereby may be provided various branch rails—for example a cross rail 9 running across from the side run 6 of the loop to the side run 7, and an auxiliary closed loop a part of one of whose side runs is coincident with a part of the side run 7 of the main loop as shown. Such an arrangement will involve the provision of points 10 at the junctions of the cross rail 9 and the side runs 6 and 7 of the main loop and at the junctions of the auxiliary loop with the side run 7 of the main loop, and will also involve the provision of a cross-over 11 at the point 55

at which the said cross rail 9 crosses the inner side run 12 of the auxiliary loop.

The auxiliary loop will be constituted in the same way as the main loop, consisting of two rigid end structures 13 and 14 from which side wires extend. These end structures may be located just within the end structures 4 and 5 of the main loop and supported therefrom by means of connecting links 15 and 16 which maintain the necessary tension in the wires of the auxiliary loop. These connections 15 and 16 are bridged as shown to enable the pulley wheels 2 and 3 to pass over the flanges 8.

The propulsion of the vehicle 1 may be effected by gravity by mounting the closed loop so that it may be tilted to and fro in such a way as to cause the vehicle to run continuously around it. Thus one of the end structures, say 4, may be fixed and the other may be mounted in such a way that it may be tilted about the longitudinal centre line of the whole loop. It will be clear that if the vehicle 1 is on this tilttable end structure, it can be made, by tilting the latter, to run down to one of the wire runs and then by tilting the end structure in the reverse direction the vehicle can be made to run down this wire run onto the other end structure which it will traverse by virtue of its own momentum. Then by reversing the tilt of the tilttable end structure once more the vehicle can be made to run back along the other wire run onto the tilttable end structure once more.

By manipulating the points 10, the vehicle 1 can be made to run over the cross wire 9 instead of the fixed end structure 4, or it can be made to run onto the auxiliary loop; and it can be made to run round this auxiliary loop in the same way as the main loop, that is to say by making one of the auxiliary end structures tilttable.

In some cases it may be preferred to make both of the end structures tilttable in both the main loop and the auxiliary loop.

In practice the end structures 4 and 5 of the main loop may be mounted at points mid way of their length on respective supporting stands or brackets 17 adapted to be rigidly mounted on the floor or supported from a wall.

Alternatively, the vehicle 1 may be propelled by means of a motor carried thereby and driving one or more of the overhead pulley wheels 2 and 3 from which the vehicle is suspended. In this case the driving pulley may be made to free-wheel automatically or under control to meet certain conditions as for instance to run through unelectrified portions of switches or to coast by gravity. Such motor may be either clockwork or electric; in the case of the motor being electric, the wire rails, end structures and other fitments may form one arm of the circuit, being connected to one terminal of the motor through the supporting pulleys; and the other arm of the circuit may be constituted by a wire 18 located underneath the loop and extending in a direction longitudinally thereof, said wire having a trolley 19 running therealong which is connected to the other terminal of the motor through a suitable connecting wire 20. As the vehicle runs round the loop the trolley 19 is pulled to and fro along the longitudinal wire 18.

To prevent the connecting wire 20 from becoming twisted and tangled, the connection thereof to the trolley 19 may be through the medium of an arm 21 mounted on the top of 75 the latter and rotatable in a horizontal plane.

The longitudinal wire 18 carrying the trolley may conveniently extend between the two supporting stands or brackets 17 near their lower ends.

In an alternative arrangement the single wire 5 rail may be replaced by a dual conductor and the current from both arms of the circuit collected by the pulleys supporting the vehicle, all as described in the specification of my co-pending application S. No. 182,044 filed December 28, 1937. 10 In this case the various fitments such as the end structures, points, cross-overs, pulley wheels and the like may have to be duly modified as will hereinafter appear.

Referring now to Figures 2 to 6, which illustrate one form which the points 10 may assume, the trunk rail portion 22 and each of the two branch rail portions 23 and 24 are constituted by strips of say brass, and the movable or switch rail portion 25 is constituted by a flexible strip 20 of spring steel having a small portion 25a of the strip brass soldered to its moving end to ease the transition from the spring steel to the brass strip. At its other end said spring steel strip is soldered to the trunk rail portion 22 and it is adapted, by virtue of its own resilience to bend alternatively into line with the branch rail portions 23 and 24.

The supporting of the trunk rail portion 22 and the two branch rail portions 23 and 24 is effected by means of a rigid metal connecting structure, comprising a horizontal flange 26 on the edge of which the portions 22 and 23 are rigidly mounted, a second horizontal flange 27 on the edge of which the portion 24 is rigidly mounted, and an integral plate structure 28 connecting said horizontal flanges and passing overhead as shown so as to permit of the passage of the pulley wheels when passing between the portions 22 and 23.

The movement of the switch rail portion 25 between its two positions is effected by means of a V shaped plate 29 of sheet metal soldered to the part 25a of the switch portion 25 and bearing a pivot pin 31 near the other end of the portion 25 which both turns and slides in a slot 32 in the flange 26. This plate 29 is formed with an upturned lug 33 whose engagement with the structure 28 limits the movement in one direction, the movement in the other direction being limited by the engagement of the part 25a with the flange 26. The switch portion 25 is biased by its own resilience to the straight through position and it may be moved to its other position by means of a string 34 attached to a lug 32a on the lug 33.

It will be appreciated that a third branch rail or indeed any number of further branch rails may be supported by an extension or extensions of the connecting structure.

When a multiple point of this character is employed, the correct alignment of the switch rail portion with the inner branch rail portion cannot be determined by means of stops engaging said switch rail portion. A suitable method of actuating the switch rail portion in this case is to bias said switch rail portion to one extreme position at which it is limited by means of a stop and pull it to the other positions by means of respective flexible wires or strings which pass through holes in a fixed bracket and carry respective stops which engage said bracket when the switch rail portion is in line with the respective branch rail portions.

For securing the three rail portions 22, 23, 24 75

to the wires each portion has its upper surface recessed for a space from its end as at 35 and a thin sheet metal hood 36 is soldered on the end of the portion so as to cover this recess and form a longitudinal hole therewith into which the wire may be inserted. The securement of the wire is then effected by means of a grub screw 37 screwed into the under side of the respective rail portion as shown.

10 Referring now to Figures 7 to 9, this illustrates a somewhat different form of point switch in which, when running straight through from the trunk portion 22 to the branch portion 23 the end of said branch portion extends close to the trunk portion as shown in Figure 8 and no switch portion is employed. When running from the trunk portion 22 to the branch portion 24, the switch portion 25b is moved into the position shown in Figure 9, into line between the trunk portion 22 and the branch portion 24, and thereby pushes the end of the branch portion 23 (which is flexible) out of the line of the trunk portion 22.

In this arrangement, as in the preceding arrangement, the trunk and branch portions are mounted on flanges 26 and 27 connected by an overhead structure 28, but, as stated the branch portion 23 extends right up to the trunk portion 22 and, throughout the major part of its length 30 is disconnected from the flange 26 so that it can be flexed to the position of Figure 9. The switch portion 25b is comprised in a single piece of metal including a vertical axis part 38 which is rotatably mounted in the structure 28 and a crank part 39 extending between said axis part and the switch portion 25b so that the latter can be moved into, and out of, its operative position as shown. The upper end of the axis part 38 is bent over to form an actuating handle 40. The end 40 of the switch portion 25b carries a downward and lateral projection 41 which engages a downward projection on the end of the branch portion 23 to prevent said switch portion and branch portion actually coming in contact and thereby 45 interfering with one flange of the pulley wheels.

This construction may suitably be lighter than that just described, the several rail portions consisting simply of wire.

It will be appreciated that the points are supported simply by the fixed rail portions being connected to the wires forming continuations therefrom, which wires are maintained in considerable tension as heretofore stated.

Referring now to Figures 10 and 11 in which 55 the cross-over 11 is illustrated, this comprises two cross rail portions crossing one another and each divided at the crossing point so as to give passage to the pulley wheels when running on the other, together with the arms by which the 60 vehicle is suspended from said pulley wheels.

Thus the four separate rail pieces 42, 43, 44, 45 are supported in correct spaced relation by means of an overhead bridging structure, and a movable rail portion 46 is provided pivoted about 65 a vertical axis 47 so as to come into line with either of the pairs 42, 44 or 43, 45.

In the arrangement illustrated the bridging structure comprises a vertical plate 48 bent at right angles as shown and carrying horizontal flanges 49 and 50 at its lower edge on whose edges the pieces 42 and 43 are mounted, and two vertical plates 51 and 52 at right angles to one another carrying horizontal flanges 53 and 54 at their lower edges on whose edges the pieces 44 and 45 75 are mounted. The plates 48, 51 and 52 are all

soldered to a common top horizontal plate 55 whereby they are secured into a rigid structure.

The movable rail portion 46 is carried by a short vertical spindle (not visible) mounted in a horizontal plate 56 secured to the underside of the flanges 49 and 50 and the lower end of this short vertical spindle carries a pinion 57 which meshes with a larger pinion 58 carried on the lower end of a spindle 59 which bears in the horizontal plates 55 and 56 and carries at its upper end a milled knob 60. Thus by rotating the milled knob 60 the movable rail portion 46 may be rotated to and fro from its two positions.

The connections from the four rail pieces to the wires are as will be seen from the drawing 15 identical with those of the switch shown in Figures 2 to 6.

The cross-over, like the points, is supported solely by the tension of the wires connected to the cross-rail portions.

In a somewhat modified form of cross-over the angle of the crossing may be adjustable. Thus, in place of the single rigid overhead bridging structure, two component overhead bridging structures may be provided pivoted together, each 25 of said component bridging structures supporting the two component pieces of each cross rail portion and the pivotal axis passing through the crossing point. In a manner analogous to the preceding arrangement, each component bridging structure will comprise underneath flanges which support the pieces of rail. The pivoting together of the two component bridging structures may be effected not only overhead but also 30 between two of the underneath flanges. A space 35 must be provided between each of the other underneath flanges and the crossing point to give passage to the said arms supporting the vehicle as will be clearly understood. With this arrangement the movable rail portion need not be provided.

It will be readily appreciated that the point structures heretofore described could also, in a somewhat analogous manner to the cross-over, be made so that the angle between the two branch 45 rail portions is adjustable.

Another device which may be incorporated is a "lay-by" or "pass-out". That is to say, a device by which the vehicle may be laid by on a short length of lay-by rail, say parallel to one 50 of the wire runs of the main loop. Such a device is indicated at 61 in Figure 1 and may consist simply of a combination of two points similar to that heretofore described with reference to Figures 2 to 6 or 7 to 9, said points having common branch rail portions at opposite ends of which the switch rail portions are located, with the trunk rail portions beyond said switch rail portions as will be readily understood. The trunk rail portions are connected as continuations 55 of the two portions of the wire run of the main loop and one of the branch rail portions constitutes the lay-by rail while the other runs straight through in line with the trunk rail portions.

The lay-by 61 is supported in the system partly by the portions of the wire run in which it is connected and partly by additional bracing wires 63 and 64 extending from the supporting structure thereof to, say, the end structure 5 of the 70 main loop and the supporting structure of the cross-over 11.

It should be noted that this lay-by can serve in the capacity of a turntable for reversing the orientation of the vehicle on the line. This is 75

illustrated in Figure 12 which is a diagrammatic plan of a lay-by. Referring to this figure the references 65 and 66 designate the trunk rail positions, 67 the common branch rail portion 5 which constitutes the straight run through, 68 the common branch rail portion which constitutes the lay-by rail and 69 and 70 the two switch rail portions.

If 2, 3 represent the two pulley wheels of the 10 vehicle 1 (both of which are capable of swiveling about a vertical axis) 2 being the driving pulley, and if the vehicle is moving from left to right of the drawing, if the switch rail portion 69 is put in the straight through position shown 15 until pulley 3 has crossed it as in position A of the vehicle and is then put in the diverting position until pulley 2 has crossed it, pulley 3 will continue along the straight line 67 and pulley 2 along the lay-by line 68 until when they reach 20 the centre position, the distance apart of the two rails then being equal to the distance apart of the two wheels and the lay-by rail 68 for its centre portion being circumferential with respect to the centre point of the straight through 25 rail 67, wheel 3 will stop at the centre point of the straight through rail and wheel 2 will continue from position B to position C with wheel 3 stationary and finally will pull wheel 3 after it. The switch point portion 70 will be at the 30 diverting position until wheel 2 has crossed it to position D after which it will be put to the straight through position until wheel 3 has crossed it. The vehicle 1 has now completely reversed its orientation.

35 Instead of each loop being supported from two end structures it can be supported from four or more corner pieces each being, in effect, one half of an end structure as heretofore described. Such corner pieces may be supported 40 from the walls of a room or from suitable brackets or from other supports such as trees; and in some cases the track need not form a closed loop. In like manner the point or lay-by structures instead of being supported by the wire 45 track may be formed so as to be directly supported from walls or other support and may accordingly assist in supporting the wire track. In all such cases, the corner pieces and/or point or lay-by structures are preferably attached to 50 their supports by links which fit into any of a number of holes and thereby admit of correct alignment and tightening up of the system.

The corner pieces, instead of being rigid may 55 be adjustable and an example of an adjustable corner piece is illustrated in Figures 13 to 15. Referring to these figures the corner piece comprises two arms 71 and 72 made of flat metal pivoted at 73 and supporting at their ends the flexible rail piece 74. To enable the rail piece 74 60 to accommodate itself to different angles of adjustment of the arms 72 and 73 the securement thereof to the arm 71 is such as to permit the rail piece to slide longitudinally. This securement takes the form of a chair 75 rigidly mounted on the arm 71. A set screw 76 passes from underneath through the arm 71 into the chair 75 and engages the rail piece 74 for securing the same firmly in the chair 75 when the required adjustment is obtained. The attachment of the 65 rail piece to the other arm 72 is rigid. The reference 77 designates a hook or the like for securing the corner piece to its support. Means may also be provided at 73 for clutching the two arms at the required adjustment. The rail piece 70 75 74 may of course be connected to the wires by

means similar to that described in connection with the switch of Figures 2 to 6.

In the case where a dual conductor is employed as heretofore stated, the end structures and corner pieces will have to be duly modified. Where a twisted dual conductor is employed continuing right through a rigid end structure or corner piece the curved edge of each horizontal plate of such end structure or corner piece instead of being formed with an upwardly projecting flange 5 10 constituting the curved end of the track, may be formed with a number of upstanding lugs which, contacting with points of like polarity, support the dual conductor at the curved end of the track, the said dual conductor being continuous throughout.

Alternatively such twisted dual conductor could be supported in a continuous channel-shaped support wholly insulated therefrom and mounted on the horizontal plate of the structure. 20

In the case of a twisted dual conductor continuing right through an adjustable corner piece, the sliding connection will preferably take the form of a short sleeve mounted on the appropriate arm of the corner piece and through which the dual conductor passes, said sleeve being completely insulated from said dual conductor. Contact will of course be interrupted at the point where the collector passes over this sleeve. 25

In the case of a parallel dual conductor continuing right through an end structure or corner piece, whether adjustable or non-adjustable, the dual conductor may have the section illustrated in Figure 16 one of the conductors only extending to the under side and being formed to be supported by chairs on the end structure or corner piece. Where the corner piece is adjustable one of such chairs will be adapted to permit of sliding of the dual conductor therein. 30 35

Figure 17 shows a slight modification of the 40 arrangement of Figure 16 in which the under-side conductor is formed with a longitudinal dove-tailed cavity in its under surface, enabling the dual conductor to be attached as desired by screws or rivets the heads of which engage in 45 the cavity as shown.

Alternatively, in the case of a parallel dual conductor the end structure or corner piece may comprise two continuous upstanding flanges 78 and 79 curved as shown in Figure 18 and insulated from one another by means of insulation 50 55. In this case the dual conductor will not extend right through the end structure or corner piece the flanges 78 and 79 serving both as the rail through the end structure or corner piece 55 and the means for completing the electrical connection between the two portions of dual conductor. Thus the ends of these two portions of dual conductor are inserted between the flanges 78 and 79 at their two ends and secured by any suitable means. When this arrangement is applied to an adjustable corner piece the two flanges 78 and 79 must form a unit which is slidable relative to one of the arms of the adjustable corner. 60 65

This latter arrangement can also serve for connecting twisted conductors in the case where opposite side by side collectors are employed so that it does not matter if a twisted dual conductor becomes, for a space, a parallel dual conductor.

In the case of points, cross-overs etc. it may be 70 found more convenient where dual conductors are employed, to make the points "dead" and in this case the vehicle will preferably have two collectors so spaced that one or other always makes contact with the live rail while the vehicle is 75

passing through the point. Where the vehicle has side by side collectors operating on dual conductors the dead rail portion of the switch may be adapted to insulate said side by side collectors from each other when passing through the switch.

When a parallel dual conductor is employed it may take the form shown in Figure 16 and the conductors may enter the switch right up to the two ends of the switch rail portion thus forming the trunk and branch rail portions. The conductors may be held down on the flanges of the switch connecting structure by means of chairs.

What I claim and desire to secure by Letters Patent is:

1. An overhead monorail track for vehicles, said monorail track comprising straight track portions consisting of a flexible rail in a state of tension, and a switch point device for guiding the vehicle from a trunk rail to either of two branch rails, said switch point device comprising a trunk rail portion forming a continuation of the trunk rail, branch rail portions forming a continuation of the respective branch rails one of said branch rail portions being normally end to end with, and close to, the trunk rail portion, and a pivoted switch rail portion capable of moving into line between the other branch rail portion and the trunk rail portion and thereby forcing the end of the former branch rail portion out of line with the trunk rail portion.

2. An overhead monorail track for vehicles, said monorail track comprising a flexible trunk rail and two flexible branch rails in a state of tension, and a switch point device for guiding the vehicle from the trunk rail to either of said branch rails, said switch point device serving as the means for attaching said rails to one another so as to support and be supported by the tension of said rails.

3. An overhead monorail track for vehicles, said monorail track comprising a flexible trunk rail and two flexible branch rails in a state of tension, and a switch point device, said switch point device comprising an overhead bridging structure, means supported by said structure for guiding said vehicles from said trunk rail to either branch rail selectively, said bridging structure serving to attach said flexible rails to one another so as to support and be supported by the tension of said flexible rails.

4. An overhead monorail track for vehicles, said monorail track comprising a flexible trunk rail and two flexible branch rails in a state of tension, and a switch point device, said switch point device comprising an overhead bridging structure, trunk and branch rail portions carried by said overhead bridging structure, means carried by said bridging structure for guiding the vehicle from the trunk rail portion to either branch rail portion selectively, said trunk and branch rail portions being connected respectively to the flexible trunk and branch rails so as to form continuations thereof, whereby said switch point device serves to attach said flexible rails to one another so that it supports and is supported by the tension of said flexible rails.

5. An overhead monorail track for vehicles, said monorail track comprising a flexible trunk rail and two flexible branch rails in a state of tension, and a switch point device, said switch point device comprising an overhead bridging structure, trunk and branch rail portions carried by said overhead bridging structure, and a switch rail portion carried by said bridging structure

with one end permanently in line with the trunk rail portion, and its other end movable alternatively into line with either of the branch rail portions selectively, said trunk and branch rail portions being connected respectively to the flexible trunk and branch rails so as to form continuations thereof, whereby said switch point device serves to attach said flexible rails to one another so that it supports and is supported by the tension of said flexible rails.

6. An overhead monorail track for vehicles, said monorail track comprising a flexible trunk rail and two flexible branch rails in a state of tension, and a switch point device, said switch point device comprising an overhead bridging structure, trunk and branch rail portions carried by said overhead bridging structure, and a switch rail portion carried by said bridging structure with one end permanently in line with the trunk rail portion, said switch rail portion being flexible so that its other end is movable alternatively into line with either of the branch rail portions selectively, said trunk and branch rail portions being connected respectively to the flexible trunk and branch rails so as to form continuations thereof, whereby said switch point device serves to attach said flexible rails to one another so that it supports and is supported by the tension of said flexible rails.

7. An overhead monorail track for vehicles, said monorail track comprising a flexible trunk rail and two flexible branch rails in a state of tension, and a switch point device, said switch point device comprising an overhead bridging structure, trunk and branch rail portions carried by said overhead bridging structure, one of said branch rail portions being normally end to end with, and close to, the trunk rail portion, and a pivoted switch rail portion carried by said bridging structure and capable of moving into line between the other branch rail portion and the trunk rail portion and thereby forcing the end of the former branch rail portion out of line with the trunk rail portion, said trunk and branch rail portions being connected respectively to the flexible trunk and branch rails so as to form continuations thereof, whereby said switch point device serves to attach said flexible rails to one another so that it supports and is supported by the tension of said flexible rails.

8. For use in an overhead monorail track for vehicles, a switch point device, said switch point device comprising means for attaching it to a flexible trunk rail and two flexible branch rails so that it serves to attach said rails to one another and supports and is supported by the tension of said rails, and comprising means whereby, when it is so attached, the vehicles are adapted to be guided from the trunk rail to either of the branch rails selectively.

9. For use in an overhead monorail track for vehicles, a switch point device, said switch point device comprising an overhead bridging structure, means for attaching said structure to a flexible trunk rail and two flexible branch rails so that it serves to attach said rails to one another and supports and is supported by the tension of said rails, and means carried by said structure whereby, when it is so attached, the vehicles are adapted to be guided from the trunk rail to either of the branch rails selectively.

10. For use in an overhead monorail track for vehicles, a switch point device, said switch point device comprising an overhead bridging structure, trunk and branch rail portions carried by

said overhead bridging structure, means for attaching said trunk and branch rail portions respectively as continuations of a flexible trunk rail and two flexible branch rails, so that the 5 structure serves to attach said rails to one another and supports and is supported by the tension of said rails, and means carried by said structure whereby the vehicle is adapted to be guided from the trunk rail portion to either of 10 the branch rail portions selectively.

11. An overhead monorail track for vehicles, said monorail track comprising a plurality of flexible rail portions in a state of tension and a track-connection device for guiding the vehicle 15 from certain of said rail portions to other of said rail portions, said track-connection device serving as the means for attaching said rail portions to one another so as to support and be supported by the tension of said rail portions.

12. An overhead monorail track for vehicles, said monorail track comprising a plurality of flexible rail portions in a state of tension, and a track-connection device, said track-connection 20 device comprising an overhead bridging structure, means supported by said structure for guiding the vehicle from certain of said rail portions to other of said rail portions, said bridging structure serving to attach said flexible rail portions to one another so as to support and be supported 25 by the tension of said flexible rail portions.

13. For use in an overhead monorail track for vehicles, a track-connection device, said track-connection device comprising means for attaching it to a plurality of flexible rail portions so that 30 it serves to attach said rail portions to one another and supports and is supported by the tension of said rail portions, and comprising means whereby, when it is so attached, the ve- 35

hicle is adapted to be guided from certain of said rail portions to other of said rail portions.

14. For use in an overhead monorail track for vehicles, a track-connection device, said track-connection device comprising an overhead bridging structure, means for attaching said structure to a plurality of flexible rail portions so that it serves to attach said rail portions to one another and supports and is supported by the tension of 10 said rail portions, and means supported by said structure whereby, when it is so attached, the vehicle is adapted to be guided from certain of said rail portions to other of said rail portions.

15. An overhead monorail track for vehicles, said monorail track comprising more than two 15 flexible rail portions in a state of tension, and a track-connection device, said track connection device comprising an overhead bridging structure, means supported by said structure for guiding the vehicle from certain of said rail portions 20 to other of said rail portions, said bridging structure serving to attach all of said flexible rail portions to one another so as to support and be supported by the tension of said flexible rail portions.

16. For use in an overhead monorail track for 25 vehicles, a track-connection device, said track-connection device comprising an overhead bridging structure, means for attaching said structure to more than two flexible rail portions so that it serves to attach said flexible rail portions to one 30 another and supports and is supported by the tension of said rail portions, and means supported by said structure whereby, when it is so attached, the vehicle is adapted to be guided from certain of said rail portions to other of 35 said rail portions.

HUGO VICTOR FLINN.
